BARRETTE OR SIMILAR ARTICLE

Paul K. Dawson, Los Angeles, Calif.

Application February 21, 1955, Serial No. 34,604

Term of patent 14 years

(Cl. D86—10)

Fig. 1.

Fig. 2.

Figure 1 is an elevational view of a barrette or similar article showing my new design; and

Fig. 2 is a side elevation thereof.

The reverse side of the figure on the barrette, apart from the outline thereof as shown in Fig. 1, bears no design.

I claim:

The ornamental design for barrette or similar article, substantially as shown and described.
